UNITED STATES PATENT OFFICE.

BERT E. HADLEY, OF LOS ANGELES, CALIFORNIA.

GAS MAKER AND COMBUSTION APPARATUS.

1,257,600.

Specification of Letters Patent. Patented Feb. 26, 1918.

Application filed September 20, 1917. Serial No. 192,348.

To all whom it may concern:

Be it known that I, BERT E. HADLEY, a citizen of the United States, residing at Los Angeles, in the county of Los Angeles and 5 State of California, have invented a new and useful Gas Maker and Combustion Apparatus, of which the following is a specification.

This invention relates to a gas generating 10 and combustion apparatus and the object of the invention is to provide an apparatus for converting kerosene oil into gas or vapors, admixing air therewith, and burning the resultant highly inflammable mixture. Another 15 object is to provide a gas generator and burner of the above character which is comparatively silent in operation, thus obviating the objectionable noise common to oil burners. Another object is to provide 20 means for effecting a rapid and complete conversion of the fuel oil into hot vapors, and to provide means for thoroughly mixing air with the vapors. A further object is to provide a vaporizer nozzle which will not 25 readily become clogged. Other objects will appear hereinafter.

The invention is illustrated in the accompanying drawings, in which:

Figure 1 is a view of the apparatus in 30 side elevation and partly in longitudinal section.

Fig. 2 is a plan view with parts broken away showing one of the mufflers in horizontal section.

Fig. 3 is a view of the apparatus in 35 perspective.

Fig. 4 is a detail vertical section of the vaporizer tip.

In carrying out my invention I employ a 40 cylindrical or tubular burner 5 which is preferably formed of pipe threaded at both ends to receive caps 6 and 7 fitted with supporting legs 8. The cylinder is formed with a series of burner openings 9 on its sides and 45 has similar openings 10 on its upper portion. The cap 6 is formed with a threaded central opening into which one end of a U-coupling 11 is screwed. Extending transversely of the cylinder is an air inlet tube 12 having a 50 threaded opening intermediate its ends into which the other end of the coupling is screwed. An aperture 13 is formed in the tube opposite the opening leading into the throat 14 formed by the coupling, and extending into this aperture is the tip 15 of a

vaporizer tube 16 disposed parallel with the cylinder 5 opposite the openings 10. The outer end of the vaporizer tube is screwed into a reduction nipple 17 removably threaded into a coupling 18 rigidly held on a 60 bracket 19 secured to the cap 7. A fuel feed pipe 20 leading from any suitable source of supply connects with the coupling 18, being detachably secured thereto by a cap 21 screwed on the coupling and engaging 65 a flange formed on the end of the pipe. The vaporizer tip 15 is constructed as shown in Fig. 4, and comprises a plug 22 screwed into the end of the vaporizer tube and having a recess 23 opening to the tube in which 70 several layers of screen, formed of wire gauze, are mounted. A plurality of passages 25 lead from the recess 23 to the outer end of the plug and communicate with tubes 26 or projections extending beyond the end 75 face of the plug. Screwed on the outer end of the plug is a cap 27 which is formed with a central end aperture 28 opening to a tube 29 extending into the cap between the tubes 26, and terminating a short distance from 80 the end face of the plug. A trap is thus formed in the tip which will prevent the discharge aperture from becoming clogged. Disposed in the vaporizer tube is a granular 85 substance 30, in this case carborundum, which is capable of being heated to a high temperature and serves when so heated to act on the oil fuel flowing through the small interstices between the grains and convert it 90 into vapors.

As a means for eliminating the noise caused by the inrush of air into the mixing chamber, the ends of the tube 12 are equipped with mufflers 31 of any suitable construction and here shown as comprising a 95 series of perforated cones 32 formed in a cylinder 33 insertible in the ends of the tube, and which cones serve to break the currents of air entering the tube so as to reduce the sound thereof. Removably inserted in the 100 outer ends of the muffler cylinders are depending air inlet pipes 34 which terminate below the burner and are flared at their lower ends. A generating pan 35 is provided and is here shown as carried beneath 105 the burner on the supports 8.

In the operation of the invention, initial generation is effected by igniting a combustible liquid, such as alcohol, in the generating pan, the resultant flame heating the 110

burner 5 and the vaporizing tube 16. The oil to be converted into gas or vapor is then admitted to the vaporizer tube through the feed pipe 20, a control valve and a check 5 valve, not shown, being suitably arranged in the feed pipe. The oil on coming in contact with the highly heated walls of the vaporizer tube and with the hot particles of carborundum within the tube is converted 10 into vapors which are ejected through the vaporizer tip into the mixing chamber, formed by the throat 14 and the central portion of the tube 12, where they are thoroughly intermixed with air admitted through 15 the mufflers. The mixed vapors and air are conveyed through the coupling 11 and passed through a baffling screen 36 disposed across the intake end of the burner 5 and thence pass out the burner openings 9 and 20 10 where they are ignited and burn with a blue flame. The flames from the burner openings 10 maintain the vaporizer tube and its carborundum contents sufficiently heated to continue the vaporizing operation. 25 By introducing the air into the mixing chamber or throat through the mufflers the burner is rendered quiet in its operation.

When it is desired to remove the vaporizer, the nipple 17 is unscrewed from the 30 coupling 18, whereupon the tip may be withdrawn from the aperture 13. In event the burner 5 becomes worn it can be unscrewed from the caps and another put in its place.

35 By constructing the parts of pipe and pipe fittings as shown, the apparatus can be built at small cost, and the various parts may be readily replaced when necessary.

40 While I have shown the burner as extending horizontally, with the vaporizer tube arranged thereabove, it has been found that it will operate effectively in any position, and may therefore be inverted, disposed on end, or inclined at various angles, according 45 to the character of the fire box in which it is installed.

Various changes may be made in the 50 details of construction without departing from the spirit and scope of the appended claims and I therefore do not limit myself to the precise form of the invention herein illustrated, for example, the muffler may be of any suitable type other than that here shown.

55 It is to be observed that the oil is fed to the vaporizer under pressure, as is common in kerosene gas generators and burners, in order to obtain the necessary force to draw a sufficient volume of air into the mixing 60 throat.

I claim:

1. In a gas maker and burner, an elongated tubular burner, an upturned U-shaped throat connecting with one end of said 65 burner, the curvature of the throat com-

mencing immediately at its point of intersection with the burner, an air intake tube arranged transversely of the burner communicating intermediate its ends with the throat immediately at the termination of 70 its curvature, a vaporizer tip extending into said tube opposite the throat, and a vaporizer tube connecting with said tip and extending parallel with the burner.

2. In a gas maker and burner, an elongated tubular burner, an upturned U-shaped throat connecting with one end of said burner, the curvature of the throat 75 commencing immediately at its point of intersection with the burner, an air intake 80 tube arranged transversely of the burner communicating intermediate its ends with the throat immediately at the termination of its curvature, a vaporizer tip extending into said tube opposite the throat, a vaporizer tube connecting with said tip and extending parallel with the burner, and a screen baffle in the burner adjacent to the lower end of the throat.

3. In a gas maker and burner, an elongated tubular burner, an upturned U-shaped throat connecting with one end of said burner, the curvature of the throat commencing immediately at its point of intersection with the burner, an air intake tube 90 arranged transversely of the burner communicating intermediate its ends with the throat, a vaporizer tip extending into said tube opposite the throat immediately at the termination of its curvature, a vaporizer 95 tube connecting with said tip and extending parallel with the burner, and granular carborundum disposed in said tube.

4. In a gas maker and burner, an elongated tubular burner, a U-shaped throat 105 connecting with one end of said burner, an air intake tube arranged transversely of the burner communicating intermediate its ends with the throat, a vaporizer tip extending into said tube opposite the throat, and mufflers arranged to act on the air entering 110 said intake tube.

5. In a gas maker, a vaporizer tube, a plug in one end thereof having a passage therethrough, a cap on the outer end of the plug having a discharge orifice, and a tube leading interiorally of the cap from said orifice terminating adjacent to the plug out of alignment with the passage.

6. In a gas maker, a vaporizer tube, a 120 plug in one end thereof, having a recess opening to the tube and formed with a passage leading from the recess to the end of the plug, a cap on the plug having a discharge orifice spaced from the end wall of 125 the plug and out of alignment with the passage in the latter, and screens disposed in the recess in the plug.

7. In a gas maker, a tube, granular carborundum therein, a plug in one end of the 130

tube, screens interposed between the plug and carborundum, a passage through the plug, a cap on the plug, and a tube opening through said cap spaced from the plug out 5 of alinement with the passage in the latter.

8. In a gas maker and burner, a vaporizer tube, a plug on the end of said tube having

a plurality of passages therethrough, a cap on the outer end of said plug having a central discharge orifice, and a tube leading 10 interiorly of the cap from said orifice terminating adjacent to the plug out of alinement with the passages in the latter.

BERT E. HADLEY.
